REMOTE-CONTROL DEVICE

Ernst Meili, Bad Ragaz, Switzerland

Application July 21, 1948, Serial No. 39,894
In Switzerland July 25, 1947

8 Claims. (Cl. 177—353)

1

The invention concerns a device for actuating optionally one or more switches over a single control channel by means of control signals of different duration.

The device according to the present invention is characterised by the feature that it possesses at least one movable element whose movement is released by the control signals and which has a definite relationship with the duration of the signals, switches being arranged in the path of said element in such a manner that they can be controlled by the movable element, at least one switching function being determined by the control signal being interrupted at an instant in which the movable element is in a position associated with the switching operation in question.

The aforesaid device differs from hitherto known devices in that on the one hand it is insensitive to disturbing impulses in the transmission channel and on the other hand requires a minimum number of switch elements. Freedom from disturbances is achieved by the condition that a signal which does not have a certain minimum duration does not cause the switch to operate. On the other hand when a certain switching operation is initiated, this operation is not adversely affected when the control signal exceeds this minimum duration by a definite amount, so that disturbing impulses which are not too long and occur immediately before or after a control signal do not disturb the control process.

In the accompanying drawings, Fig. 1 is a somewhat schematic view in top plan of a switching device according to the invention with non-essential elements omitted in the interest of clarity; Fig. 2 is a plan view similar to Fig. 1 illustrative of a modified construction; and Fig. 3 is a circuit diagram illustrating a control for the motor which is employed to drive the switch arm in rotation.

The fundamental idea on which the invention is based is explained by means of Fig. 1. By means of a control signal the switch arm A is caused to rotate in a clockwise direction by means of a special driving device. This rotary movement continues as long as the control signal lasts. The switch arm A is fitted with a switch catch K which is pivoted at M, and by means of the compression spring F₁ depending upon the position is pressed into one of the two positions of rest determined by the stops B₁ and B₂. The switch arm itself due to the spiral spring F₂ is subjected to a torque in the counter-clockwise direction, and in the starting position (shown in full lines) lies against the stop B₃, so that at the same time the catch K lies against the stop B₁.

2

If as a result of a signal the switch arm rotates, spring F₂ is wound up still further. If after a relatively short time the signal ceases, for instance when the catch K is in the dotted position 5 I, the switch arm is turned back into its original position by the spring F₂. The mechanism is expediently so constructed that the return movement occurs relatively quickly when compared with the forward movement, so that when there is 10 a series of disturbing signals the arm immediately returns to the starting point during the intervening period. In this way an accumulation of individual disturbing signals is avoided. With a longer signal, the arm moves on. The catch K 15 slides over the nose N₁. If the control signal is stopped then, the spring F₂ will turn the arm back into the position II and thus cause the pivoted lever H₁ to turn about the pivot axis Z₁. Stops B₅ and B₆ limit the movement of lever H₁ which 20 prevents the switch arm from moving back any further. In this intermediate position the device is again insensitive to intermittent disturbing signals, because although the arm commences to rotate it immediately falls back again. When a new 25 control signal occurs, the switch arm A can be rotated further until the catch K passes the nose N₂. Interruption of the signal then causes lever H₂ to pivot. These levers can be coupled with switches so that each position of a lever corresponds to a switch position. Each lever can be moved back either by a spring, or two levers can be mechanically coupled in such a way that the rotation of one lever causes the other one to be turned back. Actual switching can be arranged 30 so that each lever position corresponds to a switch position, or alternatively in a manner known per se each pressure on the lever can cause the switch to move into the opposite position. In order to return the switch arm A into its initial position after the switch has been actuated the arm is 35 revolved by a further control signal until the catch K reaches the stop B₄ (position III, shown dotted) which constitutes a trip member for the catch K. The catch is then turned by trip member B₄ into the position of rest determined by the stop B₂. As soon as the control signal ceases, the 40 switch arm is moved back to its starting position by the spring F₂ and at the same time the catch K is turned by the stop or trip member B₃ into the working position defined by the stop B₁. Naturally with this arrangement a large number 45 of levers can be controlled, so that with a suitable choice of impulse durations any desirable switching operation can be realised. Each lever can be 50 set individually by moving the switch arm out of 55

the starting position, or the control can occur in steps if after the lever H_1 has been adjusted an additional signal is given which revolves the arm until it passes the next nose that is to be actuated.

The device shown in Fig. 1 can also operate in another way if the forces which act on the catches and levers are suitably selected. Thus when revolving in a clockwise direction the catch K can first turn lever H_1 until it abuts against stop B_6 , whereupon it slides over the nose N_1 . The lever is therefore brought into the definite position when the switch arm is rotated to the right. If, however, the other switching position is desired, then the signal is interrupted after the passing of the catch and the lever is brought into the desired position by the return movement of the switch arm. It is nevertheless more expedient to provide two catches on the switch arm so that each position can be adjusted directly and independently. Such an arrangement is shown schematically in Fig. 2. In this case the switch arm is replaced by a rotatable disc S on which two catches K , K' are mounted. These catches can revolve about the axes M and M' respectively and are held by the springs F_1 and F_1' in one of the positions determined by the stops B_1 , B_2 and B_1' , B_2' respectively, whereby when abutting against the stop B_1 and B_1' the catch is in the working position and when abutting against the stop B_2 and B_2' it is in the return position. Switch pins St and St' are provided at the end of the catches, these pins being perpendicular to the plane of the disc S . In the path of these switch pins switch levers H_1 , H_2 , H_3 . . . are located which can revolve about the axes Z_1 , Z_2 , Z_3 . . . the movement of each lever being restricted by stops so as to provide two positions. These levers are enclosed on one side by guide pieces G_1 , G_2 , G_3 . . . which enable the pins St and St' to slide past easily in one direction. Levers, stops, and guide pieces are arranged in a plane parallel to the revolving disc S , so that only the switch pins St and St' project into the switching plane. The spring F_2 acts on the disc in a counter-clockwise direction. The starting position of the disc is determined by the stop B_3 . The operation of the switches occurs in an analogous manner to that described in connection with the arrangement shown in Fig. 1. When the disc is rotated in a clockwise direction, the pins St , St' slide over the guide pieces G , whereby as a result of the stepped arrangement, pin St' follows the pin St with a certain time lag. If for instance pin St is between switch levers H_1 and H_2 and pin St' is however still in front of switch lever H_1 , then an interruption of the signal with subsequent return movement of the disc causes lever H_1 to revolve in a clockwise direction. If it is desired that lever H_1 should revolve in a counter-clockwise direction, then the signal must be stopped when pin St' has slid past guide piece G_1 but pin St has not yet passed the second switch lever H_2 . In a similar way it is possible to bring the other switches into either position. After one switch has been actuated the disc remains stationary in the position until it is revolved further by subsequent control signals. The return movement of the disc to the starting position is achieved by allowing the disc to turn until the end position defined by the stop B_4 is reached. The pins St and St' are thus guided by the end trip members E , E' into the non-operative, return position. If the signal is interrupted now, the pins are in the non-operative position when the return movement takes place so that the

disc can be rotated back into the starting position defined by the stop B_3 . Shortly before reaching the starting position pins St , St' are guided back into the operative position by means of the starting trip members A , A' .

The arrangements which have been described are only two of the many constructional forms of the invention which are possible. Some of the alternative forms referred to below show that the invention can be realized in practice in many other different ways.

The return movement of the switch arm can be achieved by replacing the spiral spring F_2 by a tension spring so that the arm after executing a full revolution automatically returns to the starting position. The catch mechanism can also be constructed in various ways. For instance fixed cams can be fitted to the switch arm and catches are then provided on the levers. The adjustment of the switches can for instance be determined by the stopping of the arm or by a standstill with subsequent further rotation. In many cases it will be an advantage not to turn back the entire driving mechanism when the arm is moved back, but to provide a coupling which disengages the driving arm from the motor, so that a quick return movement is possible. This coupling device can be arranged in such a manner that a relay actuated by the control signals operates a friction or gear coupling. It may be necessary in this case to provide a damping device in order to avoid impacts. Instead of a mechanical return spring it is also possible to employ an electrical return device. The arrangement is of course not restricted to electrical control, driving, and switching systems, and any other signals, for instance mechanical or optical ones can also be used; other drives in addition to electrical drives can also be employed. Besides being used to control switches, the arrangement according to the invention can also be used in connection with throttle valves, position indicators, remote signal devices, etc.

Control devices of this kind are mainly used where various switching operations have to be controlled in optional sequence over a single control channel. Several control channels can of course be employed in the sense that the control signal can be sent over each channel. The great advantage of the present arrangement is most apparent with transmission channels with relatively strong disturbing signals, such as for instance with wireless transmission or transmission by cables, which also serve for instance as speech conductors, current supply lines, etc. An important application is the central control of consumers, tariff change-over switches, and the like, in an electrical distribution network. In this case from a central point control signals of a certain frequency are superposed on the network voltage, the receiving apparatus being so constructed that by means of a resonance system mainly only the control signals which actuate the switches are filtered out. Mechanical, electrical and also combined systems can be used for filtering out the control frequency. The energy of the control signals can be used directly for operating the drive or the signals can control a separate drive by means of a relay arrangement. In this connection the following possibilities are particularly noteworthy: the use of an electron amplifier tube, a gas-filled relay tube, an electromagnetic relay, etc. For control systems which have to operate safely for years with small powers a cold cathode glow discharge tube relay is particularly

suitable. The relay can be designed as a tube with two, three or more electrodes and operated with direct or alternating current; in the latter case it is an advantage to employ a tube with rectifier action. The current from the relay tube can either actuate the drive directly or be used to operate first an intermediate relay which puts the driving mechanism into operation. The drive can be switched in either by starting up a motor, for instance a synchronous motor, or a coupling can be actuated and the motor kept running continuously; both operations can be performed by intermediate relays. Fig. 3 shows such an arrangement with a three-electrode tube. The control frequency superposed on the network voltage L, L' is filtered out by the resonance system C, T_r and causes the glow discharge tube relay G to ignite. The current flowing through the relay tube G causes the relay R to be attracted and this latter switches in the driving mechanism. The driving motor M is supplied directly from the network.

I claim:

1. Apparatus for effecting selective operation of a plurality of switches in accordance with the duration of a control signal comprising, a control member mounted for displacement over a predetermined path from a starting position in response to the control signal, the displacement of said member being proportional to the duration of the signal, yieldable means opposing displacement of said member and tending to return the same to said starting position, a series of switch control devices distributed in spaced relation along said path and adapted to be passed in succession by said control member, each such device being cooperative with said control member and actuated by the latter upon movement thereof in the return direction in response to termination of said control signal subsequent to passing such device and prior to having passed the next said device in the series, and each such device including means preventing further movement of said control member in the return direction, and first and second trip members positioned along said path and located respectively in advance of the first and beyond the last of said switch control devices, said second trip member being operative to engage and shift said control member from an operative to a non-operative position with respect to said devices thereby to enable said control member to execute a full return movement past all of said devices to said starting position, and said first trip member being operative to engage and shift said control member back to said operative position.

2. Apparatus for effecting selective operation of a plurality of switches in accordance with the duration of a control signal comprising, a control member mounted for angular displacement over an arcuate path from a starting position in response to the control signal, the displacement of said member being proportional to the duration of the signal, yieldable means opposing displacement of said control member and tending to return the same to said starting position, a series of switch control devices distributed in spaced relation along said path and adapted to be passed in succession by said control member, each said device being comprised of a pivotally mounted lever engaged by said control member upon movement thereof in the return direction in response to termination of the signal subsequent to passing such lever but prior to having reached the next lever in the series and means limiting the move-

ment of each such lever thereby to secure said control member against further displacement in the recall direction, and first and second trip members positioned along said path and located respectively in advance of the first and beyond the last of said switch control devices, said second trip member being operative to engage and shift said control member from an operative to a non-operative position with respect to the said lever member of each said switch control device thereby to enable said control member to execute a full return movement past all of said devices to said starting position, and said first trip member being operative to engage and shift said control member back to said operative position.

3. Selective switching apparatus as defined in claim 2 wherein said control member comprises a pivotally mounted catch movable by said trip members between a pair of stops defining the said operative and non-operative positions of said control member.

4. Selective switching apparatus as defined in claim 2 wherein the means limiting movement of said lever is constituted by a stop member located at each side thereof.

5. Apparatus for effecting selective operation of a plurality of switches in accordance with the duration of a control signal comprising, a control member movable in a forward direction over a predetermined path from a starting position in response to the control signal, the displacement of said member being proportional to the duration of the signal, yieldable means cooperative with said member and exerting a force effecting return movement thereof in the reverse direction upon termination of the signal, a series of switch control devices distributed in spaced relation along said path and passed in succession by said control member, each such switch control device being unaffected when passed by said control member in its forward direction of movement but actuated by said member upon reverse movement thereof in response to termination of the signal, subsequent to passing the device, each said switch control device including means holding said control member against further movement in the reverse direction when actuated by said control member, and first and second trip members positioned along said path and located respectively in advance of the first and beyond the last of said control devices, said second trip member being operative to engage and shift said control member from an operative to a non-operative position with respect to said devices thereby to enable said control member to execute a full reverse movement past all of said devices to said starting position, and said first trip member being operative to engage and shift said control member back to said operative position.

6. Apparatus for effecting selective operation of a plurality of switches in accordance with the duration of a control signal comprising, a pivotally mounted control member supported for displacement in a forward direction over an arcuate path from a starting position in response to the control signal, the displacement of said member being proportional to the duration of the signal, yieldable means opposing displacement of said member and tending to return the same to said starting position, a series of switch control devices distributed in spaced relation along said path, each said device being comprised of a lever pivotally mounted for limited movement, and a guide member partially surrounding the lever and engaged by said control member during forward movement thereof for temporarily shifting said

control member out of the path of said lever while passing the same, said lever being engaged by said control member upon movement thereof in the return direction upon termination of the control signal subsequently to passing the lever and said control member being held by the lever when so engaged, and first and second trip members positioned along said path and located respectively in advance of the first and beyond the last of said switch control devices, said second trip member being operative to engage and shift said control member on its pivot from the path of said levers to a position sufficient to clear the guide member of each switch control device thereby to enable said control member to execute a full return movement past all of said devices to said starting position and said first trip member being operative to engage and shift said control member back to the lever path.

7. Apparatus for effecting selective operation of a plurality of switches in accordance with the duration of a control signal comprising, a support plate mounted for rotation in a forward direction from a starting position in response to the control signal, the displacement of said plate being proportional to the duration of the signal, yieldable means opposing displacement of said plate and tending to return the same to its starting position, a pair of control levers pivotally mounted on said plate, said levers each including a pin and which pins are arranged for displacement along arcuate paths of different radius in stepped relation, a series of switch control devices distributed in spaced relation along the paths of said pins, each said device being comprised of a switch lever mounted pivotally intermediate its ends with one end of each lever projecting into the path of one of said pins and the other lever end projecting into the path of the other of said pins, stop means limiting pivotal movement of each of said switch levers and a guide member partially surrounding each said switch lever and engaged by said control lever pins during forward movement thereof for temporarily shifting said control lever pins beyond the ends of said lever while passing the same, each said switch lever being engaged by one or the other of said pins upon return movement of said plate upon termination of the control signal subsequent to passage of one or the other of said pins past the same, and first and second trip members positioned along said path and located respectively in advance of the first and beyond the last of said switch control devices, said second trip member being operative to shift said

control lever pins from their working position to a return position thereby enabling said plate to execute a full return movement past all of said devices to said starting position, and said first trip member being operative to shift said control lever pins back to said working position.

8. Apparatus for effecting selective operation of a plurality of switches in accordance with the duration of a control signal comprising a glow relay tube responsive to said control signal, said tube being conductive for the duration of said signal, a control member mounted for displacement over a predetermined path from a starting position, the displacement of said member being governed by said glow tube and proportional to the conductive period of said tube, yieldable means opposing displacement of said member and tending to return the same to said starting position, a series of switch control devices distributed in spaced relation along said path and adapted to be passed in succession by said control member, each such device being cooperative with said control member and actuated by the latter upon movement thereof in the return direction in response to termination of said control signal subsequent to passing such device and prior to having passed the next said device in the series, and each said device holding said control member against further movement in the return direction once actuated thereby, and first and second trip members positioned along said path and located respectively in advance of the first and beyond the last of said switch control devices, said second trip member being operative to engage and shift said control member from an operative to a non-operative position with respect to said devices thereby to enable said control member to execute a full return movement past all of said devices to said starting position, and said first trip member being operative to engage and shift said control member back to said operative position.
